UNITED STATES PATENT OFFICE.

ALBERT KRAUTH, OF HAMILTON, OHIO, ASSIGNOR TO KRAUTH & BENNINGHOFEN, OF HAMILTON, OHIO, A COPARTNERSHIP COMPOSED OF ALBERT KRAUTH AND CHRISTIAN BENNINGHOFEN.

AUTOGRAPHIC REGISTER.

1,154,032.

Specification of Letters Patent. Patented Sept. 21, 1915.

Application filed July 1, 1912. Serial No. 706,974.

To all whom it may concern:

Be it known that I, ALBERT KRAUTH, a citizen of the United States, residing at Hamilton, in the county of Butler and State of Ohio, have invented certain new and useful Improvements in Autographic Registers, of which the following is a specification.

My invention relates to an improvement in autographic registers and concerned mainly with paper feeding mechanism for delivering the definite lengths of a continuous web to a point of severance within a limited or prescribed movement of a controlling crank handle.

The invention herein possesses similar features and utilities as that shown and described in a co-pending application filed on even date herewith and in which some of the principles are common to each, with the invention herein directed more specifically to the construction disclosed.

The object of my invention is to provide a pair of feeding rolls having their peripheries frictionally engaged with each other and positively rotated by a system of gearing in connection with a crank handle for rotating the same, the arrangement being such that a definite length of paper feed is had upon each complete rotation of the crank handle. The crank handle is adapted to engage a stop to arrest the movement thereof to definitely determine each action for the predetermined or prescribed length of paper feed necessary to deliver a complete unit, with the units comprised in a continuous web, and may be designated as record slips for record entries of individual transactions. The uses of an autographic register has a wide range well known in the art.

The features of the invention are more fully set forth in the description of the accompanying drawings, forming a part of this specification, in which:—

Figure 1 is a side elevation illustrating an autographic register, with certain elements subsidiary to the main elements of my invention shown in a general form sufficient for a clear understanding of my improvements. Fig. 2 is an end elevation thereof with certain parts thereof shown in section for a clearer exemplification. Fig. 3 is a top plan view of the forward portion of the mechanism shown in Fig. 1, disclosing my

invention with a portion of the frame shown in section.

1, 2, represent the side frames of the register, which may be of two-part form, as illustrated, with the sections thereof hinged together to provide more convenient access to the supply webs supported between the side frames. In this respect the register may be of any general or specific form or construction well-known in the art, or otherwise, but in which the general characteristics are comprised in the side frames, a writing tablet supporting between the side frames a margin frame hingedly or removably supported over the tablet, and forming the top of the register, supports for carrying the webs with a requisite amount of tension applied thereto for a proper uncoiling or feed of the paper to maintain the same in a comparatively taut condition over the writing-tablet, together with means for supporting manifolding or carbon paper between the various lengths or webs of paper fed over the tablet, for producing manifold records of each entry. The number of webs employed and the length of each unit or signature forming the components of the continuous length or web is optional to the particular usage intended.

As the primary features of this invention relate solely to feeding or delivering a predetermined length or interval of paper upon, say a complete rotation of a controlling crank handle therefor, I will only describe herein so much of the complete register necessary for a clear understanding of the construction and mode of operation of my improvements.

3, 4, represent companion coacting paper feeding rolls between which the paper is fed and engaged with the peripheries of said rolls directed frictionally toward each other, so as to impinge the paper between the same. These rolls are preferably of the same diameter, with the lower roll 3 preferably journaled in fixed bearings, while the upper roll 4 is journaled in movable bearings, comprised in the slide blocks 5, one provided for each end of the roll and each mounted in a slide-way formed in the respective side frame, with a spring 6 for each slide block for exerting a downward pressure thereto and in consequence to the roll 4. Upon the axle of each roll is fixed a gear with the

gears intermeshing with each other and preferably of the same pitch diameter, with the pitch diameter equal to the diameter of the rolls, and in which 7 represents a gear fixed to the axle of roll 4 meshing with the gear 8 fixed to the axle of roll 3. These gears in the construction illustrated are mounted adjacent to and inside of the side frame 2.

9 represents an intermediate gear fixed to the shaft 10 journaled in the side frames; the shaft 10 is provided with a gear 11, which is in mesh with the gear 8 fixed to the axle of roll 3 and 12 represents a gear in mesh with gear 9 fixed to shaft 10. Gears 15 9 and 12, as illustrated, are mounted adjacent to the outside face of the side frame 2, but it is obvious that the general arrangement of gearing and the number of gears may be modified without departing from the features of my invention. The gear 12 is shown as fixed or mounted upon a shaft 13, which projects through the side frames and upon one end of which the crank handle 14 is fixed, with the shafts, gearing and rotating elements rotated by the crank handle 14. The gear 12 is of a pitch diameter, the circumference of which equals the length of the predetermined length of slip or feed of paper desired to be had for each complete rotation or traversing circuit of the crank handle 14, with the length or unit comprising a multiple of the continuous web and its length is defined by the particular usage or form within which the registry or entry 35 is contemplated to be made. Therefore, to change the predetermined length of deliverance, so as to deliver the same upon each complete manipulating movement of the crank handle 14, a second gear 12 is substituted of a pitch diameter, having a circumference equal to the prescribed length of such change, which would change the axial line relatively of such various sizes of gearing substituted, and in the drawings, I have 45 illustrated a second bearing 15, to accommodate an axle for a reduced size of main transmitting gear 12. It is obvious, however, that the pitch diameters of the various gearing may be designed to produce the 50 same result as the construction shown and described herein, but I would regard the same as the mechanical equivalent of the preferred embodiment illustrated.

Following the principles herein, however, 55 a positive, uniform and accurate feed and delivery of each sheet comprised in the series simultaneously fed is had and when each sheet or strip contains preprinted sub-

ject-matter of duplicate form or otherwise, the relative alinement and registration is 60 not disturbed and the autograph manifold entry is made in its appropriate place, which is an essential requisite to the practical operation of an autographic register. The crank handle is shown as constructed substantially the same as that set forth in the above-mentioned copending application, and therefore, need not be elaborated on herein, but in general, comprises a movable hand hold member 16, slidably mounted within 65 the crank 14, and maintained under tension in one direction. This hand hold member 16 is provided with a stop lug 17, adapted to engage a stop 19 projected from the side frame 1, or one of its members, and 70 20 represents a cam lug opposite the stop lug 19 for directing the stop lug 17 toward the stop lug 19 if the operator should accidentally maintain the hand hold in its outward releasing position of initial disengagement with the stop lug 19, the cam lug being compulsory directed toward a rigid abutment and in consequence interrupting the circuitous movement of the crank handle and requiring a movement counter to the rotary or feeding movement of the crank handle to effect its release for a second operation. 21 represents a spring actuated pawl pivotally mounted upon the side frame, adapted to engage a ratchet wheel fixed on 80 85 the shaft 13 to prevent a reverse movement of rotating elements.

Having described my invention, I claim:—

In an autographic register, a pair of co-acting paper feeding rolls, one journaled 95 in confined bearings and the second yielding axially urged toward the other, a pair of intermeshing gears of the same relative pitch diameter, one fixed to each roll, a driving gear of a pitch diameter equal in 100 circumference to a prescribed interval length of paper to be fed, connecting with said gears in train, a two-part crank handle connecting with said driving gear, one part movable radially upon the second, and an 105 abutment projecting into the path of said movable handle part adapted to interrupt the handle motion at a point corresponding to the limit of a functioning cycle of said driving gear.

In testimony whereof, I have hereunto set my hand.

ALBERT KRAUTH.
